UNITED STATES PATENT OFFICE.

FRED H. AXELL, OF OAKLAND, CALIFORNIA.

DESIGN FOR A FLOWER HOLDER.

Application filed October 3, 1928. Serial No. 28,359. Term of patent 14 years.

To all whom it may concern:

Be it known that I, FRED H. AXELL, a citizen of the United States, residing at Oakland, in the county of Alameda and State of California, have invented a new, original, and ornamental Design for Flower Holder, of which the following is a specification, reference being had to the accompanying drawing forming part thereof.

I claim:

The ornamental design for a flower holder, as shown.

FRED H. AXELL.
